UNITED STATES PATENT OFFICE

149,929

DESIGN FOR AN AIRPLANE

Charles A. Bigelow, Houston, Tex.

Application June 5, 1946, Serial No. 130,411

Term of patent 14 years

(Cl. D71—1)

To all whom it may concern:

Be it known that I, Charles A. Bigelow, a citizen of the United States of America, residing at Houston, county of Harris, and State of Texas, have invented a new, original, and ornamental Design for an Airplane, of which the following is a specification, reference being had to the accompanying drawing, forming part thereof.

Fig. 1 is a side elevational view of an airplane showing my new design;

Fig. 2 is a top plan view;

Fig. 3 is a front elevational view; and

Fig. 4 is a front perspective view thereof.

Both sides of the design are similar.

The characteristic features of my design re-

side in the portions shown by means of full lines in the drawing.

I claim:

The ornamental design for an airplane, substantially as shown and described.

CHARLES A. BIGELOW.
